UNITED STATES PATENT OFFICE.

HARRY G. TUCKER, OF CHICAGO, ILLINOIS.

FUEL-ECONOMIZER.

1,151,308.

Specification of Letters Patent. Patented Aug. 24, 1915.

Application filed November 6, 1913. Serial No. 799,451.

To all whom it may concern:

Be it known that I, HARRY G. TUCKER, a citizen of the United States, residing at Chicago, in the county of Cook and State of Illinois, have invented certain new and useful Improvements in Fuel-Economizers, of which the following is a specification.

My invention relates to improvements in fuel economizers.

One of the objects of my invention is to provide, a longitudinally divided sectional device, to be placed within relatively, large breechings or smoke flues of furnaces, whereby to properly pre-heat and then admit the required, or suitable volume, of air, or oxygen, to the fuel being consumed, to promote combustion and to hold in check, within the furnace, from the escaping gases of combustion, the resulting heat arising from such combustion, to thereby increase the heating efficiency of the fuel.

Other and further objects of my invention will become readily apparent to persons skilled in the art from the consideration of the following description when taken in conjunction with the drawings, wherein—

Figure 1 shows a furnace to which my economizer is applied. Fig. 2 is an enlarged plan view of the device showing parts thereof and a flue in section. Fig. 3 is a longitudinal section, taken on line 3—3 of Fig. 2. Fig. 4 is a transverse section taken on line 4—4 of Fig. 3. Fig. 5 is a transverse section taken on line 5—5 of Fig. 3.

In all the views the same reference characters are employed to indicate similar parts.

In an application filed by me September 19th, 1913 and identified by Serial No. 790,683 I have shown a similar device, to that disclosed in this application, with an exception that the economizer of this application is longitudinally divided into a plurality of independent sections, so that an economizer of proper capacity may be placed within a relatively large flue without making any piece thereof too heavy for convenient transportation and handling.

Another, and more specific object of the present invention is to so fashion the respective sections that they conveniently may be placed within a flue and will mutually hold themselves in their respective places by co-operating, engaging and holding projections.

As my former application explains quite fully the theory, to which I ascribe the op-

eration of my device, I will herein describe the present structure only, believing that the same theory of operation is applicable to the present economizer.

60

The economizer is divided into three longitudinally divisible, separable, independent sections, 10, 11 and 12. The terminal parts 10 and 12 are substantial duplicates with the exception that one is adapted for 65 right hand position and the other for left hand position, with reference to the intermediate section or sections.

The three numbers are adaptable for flues of several different sizes by varying the lateral dimensions of the intermediate sections to conform with the changed diameter of the flue. The three sections operate upon the same principle and are capable of independent operation. A greater number of 75 intermediate sections may be used than shown without departing from the spirit of my invention.

The large surfaces of the surrounding walls of each of the sections serves as means 80 for exposing considerable heating surface effect to the surrounding gases and as each of the sections are made independent and non-communicating, the ingress of air into one is not disturbed by movement of the air 85 in the other. Furthermore the independence of each section prevents rotation, or other rapid movement of the air particles therein as they are admitted into the respective sections, by the impingement of air that 90 may be coming into the adjoining section. It is very desirable that the air, within the device, and each of them, be as quiescent 95 as possible in order that its diffusion into the surrounding gases may be more completely and effectively accomplished.

I will specifically describe section 10 and indicate corresponding parts of section 12 with the same reference characters with the addition of the exponent prime (').

13 is a rosette located on the outside of the flue 14 and provided with a curved cup portion 15 having a series of perforations 16' to admit air into the device in relatively small streams or separated currents. It is 105 connected to the respective sections, 10 or 12, as the case may be, through a throat 17, containing a passage way, 18, into the portion 19, of the respective section. A baffle wall 20 directs the air into the chamber 19, 110 so that the rapid motion that would be superinduced by its rush into the device, is

checked. The baffle wall 20 deflects the air into the rearward portion of the chamber, as it comes through the opening 18, which then passes down into the body part of the section, being heated by its contact with the surrounding walls thereof, until it passes around the obstruction 21 and out through perforations 22 provided in the oblique wall 24. There are a number of small perforations 22 so that the air is drawn from the device and admitted into the hot gases, within the flue, in a series of small streams. There is provided in each of the throats 17-17' of the respective sections, an opening 25 which lies near the surface of the flue 14 for admission of the air that is in contact with the flue surface. This opening is supplementary to the plurality of openings provided in the respective rosettes. The sections 10 and 12 are provided with projections 26 which register with grooves formed between the ribs 27 on the central section 11, so as to hold the radially wedge shaped central section in proper register with its companion section and to hold it in place within the flue. The sections 10 and 12 are held in the flue, and the rosettes 15 are secured thereto, by means of bolts 28 as clearly shown in Fig. 4. The central section 11 is provided with an opening 29 overlain by a lip 30 for admission of the air into said section. The air, passing through an opening 31, strikes against a baffle plate 32 to check its movement and to render it quiescent. The baffle plate 32 is part of the wall surrounding an opening 33, to lend additional heating surfaces for impingement of the incoming air. Another opening, 34 is also provided in the central section, having a wall 35 adapted for the same purpose. The walls surrounding these openings are tapered with the smaller ends facing so that the air when striking the wall 35 will be checked to some extent and at the same time it will be heated and will finally pass out through the plurality of openings 36 provided in the tapered wall 37 of the section 11. The caps of the rosettes 15-15' are held in place on the main body portion of the respective sections by screw bolts 38 so that

these caps may readily be removed and access to the interior device may thus be had, if desired, without bodily moving the device from its position within the flue. 55

The best results are attained, in the use of my device, when it is placed to the side of the central, longitudinal axis of the flue, and it is immaterial whether the three sections are located in close proximity to each other or whether they are distributed further distances apart around the interior of the flue. The present arrangement, however, produces more economical results in the construction and application of the device and answers every purpose. 65

Having described my invention what I claim is:—

1. A device of the character described comprising a plurality of relatively long, 70 separate, independent, hollow structures, each structure provided with a baffled air inlet and a plurality of small outlets, said structures adapted for location in a flue, and having their longitudinally disposed, 75 contacting surfaces substantially conforming to the inner surface of the flue walls and in contact therewith; means for securing two of said structures to the flue wall and means, provided on said two terminal 80 structures to hold the intermediate structure in place.

2. A device of the character described, comprising two substantially duplicate relatively long, separate, independent, hollow 85 structures, one adapted for right hand position and the other for left hand position; means for holding said structures in place in a flue; an intermediate structure held in place by means provided on each of the terminal structures, each said structure provided with a baffled air inlet and a plurality of small air outlets and means provided in each of the structures for heating the incoming air. 90

95 In testimony whereof I hereunto set my hand in the presence of two witnesses.

HARRY G. TUCKER.

In the presence of—

FOREE BAIN,
MARY Y. ALLEN.
